CLAIM

The ornamental design for a barbecue tool with contour grip, as shown and described.

DESCRIPTION

FIG. 1 is a top plan view of a barbecue tool with contour grip showing my new design;

FIG. 2 is a side elevational view thereof, the opposite side being a mirror image;

FIG. 3 is a bottom view thereof;

FIG. 4 is an end view thereof; and,

FIG. 5 is a sectional view taken along the line 5—5 of FIG. 2. The broken line showings form no part of the claimed design.
